UNITED STATES PATENT OFFICE.

JOHN FOX JENNENS MALONE, OF NEWCASTLE-ON-TYNE, ENGLAND.

HEAT ENGINE OPERATED BY THE EXPANSION OF LIQUIDS.

Application filed February 27, 1924, Serial No. 695,534, and in Great Britain February 28, 1923.

This invention relates to heat engines of the type described in my U. S. Patent No. 1,487,664 of March 18, 1924 in which the engine is operated by the expansion of a liquid alternately displaced from one end to the other of a cylinder of which the ends are maintained at a constant difference of temperature by a source of heat and by a cooling medium.

10 According to this invention the cylinders in which the rams reciprocate and the mechanism for converting the reciprocating motion of the rams into the rotary motion of a shaft are separate from, though in communication 15 with, the displacer cylinders in which the working medium is alternately heated and cooled.

Other novel features of the invention will be described later in the specification.

20 The pressures and temperatures used are limited only by the strength of the materials employed. The temperature range may be from about 90° F. to 650° F. and the lower pressure must be such that the working medium remains in the liquid state at the highest temperature. It is, however, conceivable that under some special conditions the temperature of the liquid at the hot end of the displacer cylinders may be raised above the 25 critical point and some small portion of the liquid may be converted into the gaseous state, but such conditions would not arise in the normal working conditions contemplated.

30 In the accompanying drawings, which represent an example of an engine according to the invention,—

Fig. 1 is an end elevation, partly in section, of the power cylinders and gearing.

Fig. 1^a is a view of the lower portion of Fig. 40 1 on a larger scale.

Fig. 2 is a front elevation, mainly in section, of the apparatus as a whole.

Fig. 3 is a vertical longitudinal section of the trip gear,

45 Fig. 3^a is a horizontal longitudinal section of the trip gear, and

Figs. 4-6 are explanatory diagrams.

1 are cylinders (the displacer cylinders) closed at each end and containing a liquid, 50 which may be assumed to be water, and displacer rods 2 which transfer the liquid at suitable parts of the working cycle of the engine from one end to the other of the cylinders 1. The cylinders 1 are inserted in gas-tight apertures 3 provided in a casing 4 traversed by the fire gases from a furnace or otherwise main-

tained at a high temperature. The ends of the cylinders in the casing are connected to metal blocks 5. The other ends of the cylinders are inserted in water-tight apertures 6 in a tank 7 and are maintained at a low temperature by a constant flow of water through the tank.

The cylinders 1 are divided into two sets connected respectively by pipes 8 and 9 with the lower and upper power cylinders 10 and 11.

In the example illustrated the rams 12 and 13 pass through glands 14 and 15 provided at the inner ends of the cylinders 10 and 11. The rams are connected to a crosshead 16 to either side of which are respectively pivoted connecting rods 17 and 18 which engage with crank pins 19 and 20 of a crank 21.

The glands are provided with cup leathers 75 as shown at 14^a in Fig. 1, in connection with the gland 14. This figure also shows the rod 23 entering the gland.

Nuts 22 are secured to the outer ends of the rams 12 and 13 and rods 23 inserted in and 80 coaxial with the rams are provided with external threads 24 of coarse pitch engaging with similar internal threads in the nuts 22. Longitudinal displacement of the rods 23 is prevented by the engagement of the heads 25 in recesses 26 provided in plugs 27 screw 85 threaded respectively into the outer ends of the cylinders 10, 11. The inner ends of the recesses 26 are closed by rings 28 screw threaded into the plugs 27, with openings to allow 90 the passage of the rods 23 but not of the heads 25. Packing to prevent leakage of liquid past the junction of the plug and cylinder is inserted at 29.

95 As the rams 12 and 13 and with them the nuts 22 reciprocate, the rods 23 are rotated and this rotation is imparted to pinions 30, secured to the rods 23, and engaging with rack 31 by which a corresponding reciprocal motion is produced in rods 32, arranged at right angles to the rams 12, 13. Preferably, the pitch of the threads in the nuts 22 and on the rods 23 is such that the pinions 30 rotate through a complete revolution during one stroke of the rams. Lateral 100 extensions 33 of the cylinders 10, 11 provide guides for the reciprocating motion of the rods 32.

105 The rods 32 are connected, by trip gears contained in guide casings 34 (one of such trip gears being shown diagrammatically in Fig. 2 and in detail in Fig. 3 and 3^a), to similar

rods 35 provided with racks 36 engaging with pinions 37 secured to rods 38. The rods 38 are provided with long pinions engaging racks 39 secured to the cold ends of the displacers 2, which are consequently reciprocated in conformity with the movements of the rods 35.

The intervention of a trip gear is necessary between the rods 32 and the rods 35, since the displacers move with the rams through a part only of the stroke of the latter.

In the example illustrated in Figs. 3 and 3^a, the rods 32 and 35 are each adapted to slide in a guide casing 34. The rods 32 are provided with heads 40 to each of which is pivoted a pawl 41 adapted to engage against shoulders 42 and 43 in extensions 44 of the rods 35. A double faced cam 45 is secured in each guide 34 and these cams 45 are adapted, during the movement of the rods 32, to engage and raise the pawls 41 against the action of springs 46 from the shoulders 42 of the rods 35 after the rams have completed a certain portion of their downward strokes. This permits the rams to finish their strokes while the displacers are stationary. During the upward strokes of the rams, the opposite movement to that just described takes place, the first part of this movement being effected without any movement of the displacers, whereas during the remainder of the movement, the rams 11 and 12 and the displacers 2 move together.

In order to vary as may be required the portion of the stroke in which the displacers are stationary, the position of the block 45 may be altered and for this purpose it may be provided with a pin 46^a adapted to be inserted in any one of holes 47 provided in the guide casing 34.

The liquid in the power cylinders 10 and 11 is preferably oil and in contact with the liquid, which as stated above may be water in the displacer cylinders.

The action may be explained as follows with the aid of the explanatory diagrams Figs. 4-6.

From the dead centre position of the crank shown in Fig. 1 and indicated at the point C in Fig. 4, the rams are descending and the displacers 2 of the lower set (Fig. 2) move from the left towards the right and displace the liquid from the heated to the cooled end at a constant low pressure. When the point D (Fig. 4) of the cycle is reached, the displacers are disconnected from the trip gear. The ram 12 has moved from C to D (Fig. 6) and the displacers are in the position E of Fig. 5. The rams (Fig. 6) are permitted, by contraction of the liquid caused by progressive cooling after the liquid has been displaced to the cool end of the displacer cylinders, to complete the descent while the displacers are stationary, movement of the displacers of the upper set having meanwhile caused expansion of the liquid above the upper ram to keep pace with the contraction of liquid below the lower

ram. When the lower dead centre A is reached, the displacers are still at the hot end of their cylinders, as shown at E (Fig. 5), and the ram 12 is at A (Fig. 6).

The rams now rise as the crank rotates from A to B (Fig. 4), the liquid is displaced from the cold to the hot end of the lower set of displacers as shown at F (Fig. 5) and the corresponding displacement in the opposite direction having occurred at the same time in the upper set of displacers, the rams have completed half their upward stroke indicated at B of Fig. 6. The range of temperature is so chosen that the decrease of volume due to the cooling is approximately equal to the increase of volume of the liquid in the displacers as the temperature of that volume is raised on passing from the cold to the hot end of the displacer cylinders. This quadrant of the cycle is the period during which power is developed in the engine and the energy generated depends upon the product of the pressure applied and the increase of volume of the liquid in passing from the cold to the hot end of the displacers.

In the last quadrant of the cycle as the crank rotates from B to C the rams rise to the position C while the displacers are stationary the volume of liquid increasing under progressive heating thereof.

The action of the ram 13 in the upper cylinder 11 in connection with the other set of displacers is similar to that described with reference to the ram 12, but with the difference that as the ram 13 descends the space available for the liquids is increased and the pressure consequently falls, so that the power is developed as the crank passes from the position C to position D.

The volume swept through by each ram when moving with the displacer is equal to the change of volume of the liquid as it passes from one end to the other of the corresponding set of displacer cylinders, and the volume swept through by the ram in its further movement when the displacer is stationary is equal to the change of volume due to the compression of the liquids and the increased capacity of the containing vessels at the higher pressure.

It is understood that a portion only and not the whole volume of the liquid is displaced from one end to the other of the displacer cylinders and that the range of temperature of any portion of the liquid in the displacer cylinders is only a fraction of the difference of temperature at which the two ends of these cylinders are maintained.

In an experimental plant, the length of the displacers was 75 inches, the stroke of the displacers 5 inches, the diameter of the displacers 5/8 of an inch, the width of the annular space between the displacers and the internal wall of the cylinders 3/64 of an inch, the travel of each portion of the film of liquid

in the annular space was 15 inches and the consequent change of temperature of each portion of liquid only 1/5 of the temperature difference between the hot and cold ends of 5 the displacer cylinders.

In order that the volume of the liquid in the displacer cylinders and consequently the pressure generated may be varied as required, a tank 48 is connected by means of a valve 49, 10 branch pipe 50, and valves 8^a and 9^a to the displacer cylinders by pipes 8 and 9, respectively.

The tank 48 is also connected by a pump 51 and valve 52 to an accumulator 53, which communicates through a valve 54 and pipe 15 55 with the pipe 50.

By opening the valve 8^a or valve 9^a and valve 49 liquid can flow from the displacer cylinders into the tank 48 to effect the required reduction in the quantity of liquid and consequently in the pressure. Liquid from the tank 48 can be pumped into the accumulator 53 by working the pump 51 and delivered as required into the pipe 50 to add to the volume present at any time in the displacer cylinders.

In order to start the engine, liquid can be supplied at low pressure from the accumulator 53 to the displacer cylinders, the casing 5 heated and the pump 51 worked to increase 30 the pressure in the liquid system. When the engine is started the pump 51 can be driven by any suitable means.

Having thus described the nature of the said invention and the best means I know 35 of carrying the same into practical effect, I claim:—

1. A heat engine comprising in combination a plurality of liquid-containing working cylinders, a plunger reciprocating in each 40 of said cylinders, a set of displacers associated with each working cylinder, a set of intercommunicating liquid-containing cylinders wherein said displacers are contained, means operated by said plungers for reciprocating said displacers and thereby alternately 45 transferring liquid to opposite ends of said displacer cylinders, said plunger operated means being adapted to be connected with and disconnected from said displacers, means controlling the connection and disconnection 50 of said plunger operated means and said displacers, said controlling means being adjustable to regulate the times of connection and disconnection of said plunger operated means 55 and said displacers, means for maintaining the ends of said displacer cylinders at a difference of temperature and means connecting each set of displacer cylinders with each associated working cylinder.

2. A heat engine comprising in combination a liquid-containing working cylinder and a plunger reciprocating therein, a set 60 of displacers and a set of intercommunicating liquid-containing cylinders wherein said displacers are contained, means operated by said

plunger to reciprocate said displacers with said plunger through a part of the stroke of the plunger and thereby alternately transfer liquid to opposite ends of said displacer cylinders, said plunger operated means being engageable with and disengageable from said displacers, means controlling the engagement and disengagement of said plunger operated means with said displacers, said controlling means being adjustable to regulate the times of engagement and disengagement of said plunger operated means with said displacers, means for maintaining the ends of said displacer cylinders at a difference of temperature and means connecting said displacer cylinders with said working cylinder.

3. A heat engine comprising in combination a plurality of liquid-containing working cylinders, a plunger reciprocating in each of said cylinders, a set of displacers associated with each working cylinder, a set of intercommunicating liquid-containing cylinders wherein said displacers are contained, means operated by said plungers to reciprocate said displacers through a part of the stroke of the 90 plungers and thereby alternately transfer liquid to opposite ends of said displacer cylinders, said plunger operated means being engageable with and disengageable from said displacers, means controlling the engagement and disengagement of said plunger operated means with said displacers, said controlling means being adjustable to regulate the times of engagement and disengagement of said plunger operated means with said displacers, means for maintaining the ends of said displacer cylinders at a difference of temperature and means connecting each set of displacer cylinders with each associated working cylinder.

4. A heat engine comprising in combination a liquid-containing working cylinder and a plunger reciprocating therein, a set of displacers and a set of intercommunicating liquid-containing cylinders wherein said displacers are contained, a rack and means operated by said plunger to reciprocate said rack, a second rack coaxial with said first-mentioned rack and engageable and disengageable with the latter, means for causing the engagement and disengagement of said racks, said last-named means being adjustable to regulate the times of engagement and disengagement of said racks and means associated with said second rack to reciprocate 120 said displacers and thereby alternately transfer liquid to opposite ends of said displacer cylinders, means for maintaining the ends of said displacer cylinders at a difference of temperature and means connecting said displacer cylinders with said working cylinder.

5. A heat engine comprising in combination a plurality of liquid-containing working cylinders, a plunger reciprocating in each of

said cylinders, a set of displacers associated with each working cylinder, a set of intercommunicating liquid-containing cylinders wherein said displacers are contained, a rack 5 associated with each plunger and means operated by said plungers to reciprocate said racks, racks respectively coaxial with said first mentioned racks, said first-named racks being engageable with and disengageable 10 from said second-named racks, means controlling the engagement and disengagement of said racks, said means being adjustable for regulating the times of engagement and disengagement of said racks, and means associated with said second mentioned racks to reciprocate respectively said displacers, and thereby alternately transfer liquid to opposite ends of said displacer cylinders, means for maintaining the ends of said displacer cylinders 15 at a difference of temperature, and means connecting each set of displacer cylinders with each associated working cylinder.

6. A heat engine comprising in combination a liquid-containing working cylinder and a plunger reciprocating therein, a set of displacers and a set of intercommunicating liquid-containing cylinders wherein said displacers are contained, a rack and means operated by said plunger to reciprocate said rack, 20 a second rack coaxial with said first mentioned rack, said second mentioned rack having an extension provided with spaced recesses, a pawl pivoted on said first mentioned rack adapted to engage in one or other of 25 said recesses, a guiding casing for said racks, a beveled-ended block secured to said casing and adapted to be adjusted to raise said pawl from said recesses at different parts of the stroke of said first mentioned rack, means associated with said second rack to reciprocate 30 said displacers and thereby alternately transfer liquid to opposite ends of said displacer cylinders, means for maintaining the ends of said displacer cylinders at a difference of temperature and means connecting said displacer cylinders with said working cylinder.

7. A heat engine comprising in combination a plurality of liquid-containing working cylinders, a plunger reciprocating in each 35 of said cylinders, a set of displacers associated with each working cylinder, a set of intercommunicating liquid-containing cylinders wherein said displacers are contained, a rack associated with each plunger and reciprocated by the movement of such plunger, a second rack in longitudinal alignment with each of said first-mentioned racks, a guiding casing for each pair of aligned racks, each of 40 said second racks having a shoulder, a pawl carried by each of said first racks for engagement with the shoulder of the aligned second rack, a bevel-ended block in each of said guiding casings and adjustable lengthwise of the latter for engaging and lifting the pawl of the 45 first rack from the shoulder of the second

rack working in such casing at different parts of the stroke of such first rack, means associated with each of said second racks to reciprocate one of said sets of displacers and thereby alternately transfer liquid to opposite ends of said displacer cylinders, means for maintaining the ends of said displacer cylinders at a difference of temperature and means connecting each set of displacer cylinders with each associated working cylinder.

8. A heat engine comprising in combination a liquid-containing working cylinder and a plunger reciprocating therein, a set of displacers and a set of intercommunicating liquid-containing cylinders wherein said displacers are contained, means connecting said displacer cylinders and said working cylinder, a screw threaded nut on the outer end of said plunger, a rod coaxial with said plunger and having a coarse pitched thread engaging with the screw thread of said nut, means for preventing the axial movement of said rod, a pinion on said rod and means actuated by said pinion for causing said displacers to reciprocate with but only through part of the stroke of said plunger and thereby alternately transfer liquid to opposite ends of said displacer cylinders, and means for maintaining the ends of said displacer cylinders at a difference of temperature.

9. A heat engine comprising in combination a liquid-containing working cylinder and a plunger reciprocating therein, a set of displacers and a set of intercommunicating liquid-containing cylinders wherein said displacers are contained, means connecting said displacer cylinders to said working cylinder, a screw threaded nut on the outer end of said plunger, a rod coaxial with said plunger, and having a coarse pitched thread engaging with the screw thread of said nut, a plug removably secured to the outer end of said cylinder, said plug having a recess and said rod having an enlarged head engaging in said recess, a pinion on said rod and means actuated by said pinion for causing said displacers to reciprocate with but only through part of the stroke of said plunger and thereby alternately transfer liquid to opposite ends of said displacer cylinders, and means for maintaining the ends of said displacer cylinders at a difference of temperature.

10. A heat engine comprising in combination a liquid-containing working cylinder and a plunger reciprocating therein, a set of displacers and a set of intercommunicating liquid-containing cylinders wherein said displacers are contained, means connecting said displacer cylinders to said working cylinder, a screw threaded nut on the outer end of said plunger, a rod coaxial with said plunger and having a coarse pitched thread engaging with the screw thread of said nut, means for preventing the axial movement of said rod, a pinion on said rod, a rack engaged by said

pinion, a second rack coaxial with said first mentioned rack and separably connected thereto, a pinion engaging said second rack, a rod secured to said last-named pinion, a set of pinions carried by said rod, the displacers 5 having racks engaged, respectively, by the pinions of said set of pinions to reciprocate said displacers having racks and thereby alternately transfer liquid to opposite ends of said displacer cylinders, and means for maintaining the ends of said displacer cylinders at 10 a difference of temperature.

11. A heat engine comprising a plurality of working cylinders closed at each end, a plunger reciprocating in each cylinder, a crank 15 shaft actuated by the reciprocation of said plungers, a liquid contained in each of said cylinders adapted to contain a liquid at one end thereof, displacers, and liquid-containing cylinders containing said displacers disposed 20 independently of said working cylinders, liquid in said displacer cylinders, pipes connecting the working cylinders with the displacer cylinders, means operated by said plungers for reciprocating said displacers in 25 said displacer cylinders, and means for maintaining a difference of temperature between the ends of said displacer cylinders, an accumulator, a pump connected to said accumulator, pipes connecting said accumulator with 30 said displacer cylinders, and valves between said pump and said accumulator and between said accumulator and said pipes.

12. A heat engine comprising a plurality of working cylinders closed at each end, a plunger 35 reciprocating in each cylinder, a crank shaft and means for connecting said plungers to said crank shaft, each of said cylinders adapted to contain a liquid at one end thereof, displacers, and liquid-containing cylinders containing said displacers disposed independently of said working cylinders, pipes connecting the working cylinders with the displacer cylinders, means operated by said 40 plungers for reciprocating said displacers in said displacer cylinders, and means for maintaining a difference of temperature between the ends of said displacer cylinders, an accumulator, a pump connected to said accumulator, pipes connecting said accumulator with 45 said displacer cylinders, valves inserted between said pump and said accumulator, and between said accumulator and said pipes, a liquid-containing tank connected to said 50 pump, pipes connecting said tank with said displacer cylinders and valves inserted between said tank and said last mentioned pipes.

13. A heat engine comprising in combination a working cylinder and a plunger reciprocating therein; a liquid volume modifier comprising a set of inter-communicating displacer cylinders and a set of displacers working in said cylinders, means for maintaining the ends of said displacer cylinders at different temperatures; a conduit connecting 55

said displacer cylinders and said working cylinder and forming therewith a continuous liquid containing chamber; means actuated by said plunger for imparting movement to said displacers and adapted to be connected 70 to and disconnected from said displacers; and adjustable means for regulating the times of connection and disconnection of said plunger actuated means with said displacers to maintain the volume of liquid in said 75 chamber substantially equivalent to the volume of said chamber during reciprocations of said plunger.

14. A heat engine comprising a crank shaft, a cylinder having a closed end, a plunger 80 reciprocating in said cylinder and in driving connection with a crank of said crank shaft, a liquid volume modifier connected to the space between the plunger and the closed end of said cylinder and forming with said space 85 a continuous liquid-containing chamber, means adapted to be connected to and disconnected from said modifier, said means being operated by said reciprocating plunger to vary the action of said modifier, and a connection control adjustable to regulate the times of connection of said means with and its disconnection from said modifier to cause the modifier by the variations in the temperature of said liquid to maintain the volume 95 of liquid in said continuous chamber substantially equivalent to the total volume of said continuous chamber during the reciprocations of said plunger.

15. A heat engine comprising a reciprocating cross-head, a pair of cylinders each closed at one end, a plunger working in each of said cylinders, means connecting each of said plungers with said cross-head to cause said plungers to reciprocate in opposite directions to one another relatively to the closed end of their respective cylinders, a liquid volume modifier in communication with the space between the plunger and the closed end of each of said cylinders and forming therewith a continuous liquid containing chamber, means actuated by each of said plungers and adapted to be connected to and disconnected from the modifier associated therewith for imparting movement from said plunger to said liquid volume modifier, and a connection control adjustable for regulating the times of connection and disconnection of each of said means and its associated modifier to cause each of said modifiers by varying the temperature of the liquid content therein to maintain the volume of liquid in its respective continuous chamber equivalent to the volume of said chamber during reciprocations of its respective plunger.

16. A heat engine comprising, in combination, a motor cylinder closed at one end and having a plunger reciprocating therein, a crank shaft in driving connection with said plunger, a liquid volume modifier comprising 120

- a plurality of displacer cylinders having a free channel of communication with one another, a displacer in each of said displacer cylinders, means for maintaining a substantially predetermined difference of temperature between the opposite ends of the interiors of said displacer cylinders, a conduit connecting said free channel with the space between the plunger and the closed end of said 5 motor cylinder and forming therewith a continuous liquid containing chamber, means operated by said plunger and adapted to be

connected to and disconnected from said displacers to shift said displacers in said displacer cylinders, and a connection control adjustable for regulating the times of connection and disconnection of said means and said displacers to cause variations in volume of said liquid to keep pace with variations in the volume of said chamber due to reciprocations of said plunger. 15 20

In testimony whereof I have signed my name to this specification.

JOHN FOX JENNENS MALONE.
